UNITED STATES PATENT OFFICE

JAMES W. PICKERING, OF RUTHERFORD, NEW JERSEY

DESIGN FOR A DECK OF PLAYING CARDS

Application filed April 12, 1932. Serial No. 43,464. Term of patent 7 years.

To all whom it may concern:

Be it known that I, JAMES W. PICKERING, a citizen of the United States, residing at Rutherford, in the county of Bergen and State of New Jersey, have invented a new, original, and ornamental Design for a Deck of Playing Cards, of which the following is a specification, reference being had to the accompanying drawing, forming part thereof.

The drawing shows face views of certain cards from a deck of playing cards illustrating my design. The same scheme of design is carried out in the entire deck.

I claim:

The ornamental design for a deck of playing cards as shown and described.

JAMES W. PICKERING.
